No. 873,184.

PATENTED DEC. 10, 1907.

F. L. STONE.
DISPLAY CARD RACK.
APPLICATION FILED SEPT. 3, 1907.

UNITED STATES PATENT OFFICE.

FRED L. STONE, OF DENVER, COLORADO.

DISPLAY CARD-RACK.

No. 873,184.

Specification of Letters Patent.

Patented Dec. 10, 1907.

Application filed September 3, 1907. Serial No. 391,010.

To all whom it may concern:

Be it known that I, FRED L. STONE, a citizen of the United States, residing at Denver, in the county of Denver and State of Colorado, have invented certain novel and useful Improvements in Display Card-Racks, of which the following is a full, clear, and accurate description and specification, reference being had to the accompanying drawings, 10 which are hereby made a part thereof.

My invention relates to that class of card-racks in which the cards, or similar articles, are shown or displayed upon perpendicular panels, supported upon a portable standard.

15 The principal objects of my invention are:— to provide a rack which will, with a minimum amount of space occupied, afford a maximum amount of display surface, thus effecting an economy of space in certain 20 classes of establishments where such economy is a prime object; to afford a device which will, with permanent and efficient structure, combine attractiveness of appearance and ease of manipulation, and at the same time 25 be perfectly portable and stable; and generally, to cheapen the cost and improve the construction and efficiency of this class of devices.

To accomplish these objects, the invention 30 consists in the novel construction of the component parts of the device, and of their arrangement and combination, as herein-after described and set forth in the claims.

The device consists of a supporting standard, a sustaining frame raised thereon, and swinging panels hinged between the upper and lower members of the frame, the said panels being provided with means to hold and display cards, or similar articles.

40 In the accompanying drawings, Figure 1 shows a front view of the device as a whole, the panels being swung apart to right and left. Fig. 2 is a top view of the same, showing the arrangement of the two wings of the 45 supporting frame. Fig. 3 is a detail view of one face of one of the panels, showing means for holding and displaying cards. Fig. 4 is a plan view of one of the panels, showing means for holding and displaying, and also 50 the flange for spacing.

The same figures of reference indicate the same parts in the different views shown.

A. is the supporting standard. The parts B. B', C. C', D. D'. D''. together constitute 55 the sustaining frame raised upon the standard. B. B'. and C. C'. are the upper and

lower members, respectively, of this frame, and are arranged to form two wings at right angles with each other, the apex of the right angle being at the center of the standard, 60 from which rises the rod D. This rod D., together with rods D' and D'', rising also from the standard constitute the perpendicular parts of the frame, and when brought into attachment and adjustment with parts 65 B. B'. and C. C'. serve to hold the whole firmly in proper position. This arrangement at right angles of the two wings of the frame is made primarily to adjust and distribute the weight of the device, and particularly of the panels, so that the center of 70 gravity will be well within the base, and the whole will be rendered perfectly stable. All these parts should be made preferably of cast iron, and it will be evident that the standard 75 and lower members of the frame may be cast as one piece. The upper members, at right angles with each other, may be similarly cast as one piece.

The various parts mentioned may be very 80 appropriately assembled and held firmly in proper combination by means of any desirable thread, or thread and nut, adjustment. The arrangement of the two wings of the frame at right angles with each other is most 85 clearly shown in Fig. 2. E. E. etc. represent the various swinging panels, upon which are disposed the means for holding and displaying the cards, or other articles. In the preferable form of construction, these 90 panels should be of sheet metal, and the means of holding and displaying should be in the form of skeleton pockets of similar metal arranged and disposed upon the surfaces of the several panels, as indicated in the several figures by F. In the form of construction shown, the side, end and bottom of each skeleton pocket is formed of the metal piece G. which is bent at a right angle inwardly to form the part a. and b., and at a right angle 95 upwardly to form the part c. the bottom, and which metal piece may be soldered to, or fixed in slots in, the surface of the panel. H. H. etc. indicate the means by which the various panels are hinged into the sustaining 100 frame.

In order to properly space the several panels and prevent them from catching one upon the other when moved the top and bottom of each panel is constructed with a 110 flanged part I. I. at right angles with the general surface of the panel, which flange

will; when the panels are brought close together, come in contact with the next panel at such distance away as to leave them both free to play back and forth. This feature 5 will also provide, when all the leaves are closed together, a means to keep dust, or other substances from falling upon the cards from above.

Changes within the scope of the invention 10 may manifestly be made without altering its spirit.

Having described my invention, my claims are:—

1. In the construction of display card-racks, a portable supporting standard, a sustaining frame raised thereon, said frame consisting of two wings set at right angles with each other and apexing at the center of the standard, a number of swinging panels 15 hinged between the upper and lower members of the sustaining frame with means for holding and displaying cards, or similar ar-

ticles, conveniently disposed upon the surfaces of each panel, and each panel bearing at top and bottom a spacing flange, substantially as described. 25

2. In the construction of display card-racks, a sustaining frame raised upon a supporting portable standard, and consisting of two wings set at right angles with each other and apexing at the center of the standard, and carrying hinged swinging panels, which panels bear upon their surfaces means for holding and displaying cards, or similar articles, with spacing flange at the top and bottom of each panel, substantially as described. 30 35

In testimony whereof I affix my signature in the presence of two witnesses.

FRED L. STONE.
